UNITED STATES PATENT OFFICE

2,509,551

ROLLING INVALID TOILET CHAIR

Harold O. Woods, Ainsworth, Nebr.

Application December 9, 1946, Serial No. 715,005

1 Claim. (Cl. 155—31)

1 This invention relates to portable invalid toilet chairs.

An object of this invention is to provide a movable toilet chair which has been designed for invalids and is so constructed that an invalid may be easily shifted from a wheel chair or a bed onto the toilet chair and the latter then moved to dispose the chair about the toilet bowl, thereby eliminating undue shifting or lifting of the patient.

Another object of this invention is to provide a chair of this type which includes a pivoted seat extension adapted to engage upon the wheel chair or bed so that the patient may easily slide from the wheel chair or bed onto the chair seat.

A further object of this invention is to provide a chair of this type which can be made of tubular material so as to form a relatively lightweight and strong chair which is mounted on rollers so that the chair can be easily moved.

With the above and other objects in view, my invention consists in the arrangement, combination and details of construction disclosed in the drawings and specification, and then more particularly pointed out in the appended claim.

In the drawings,

Figure 1 is a detail front elevation of an invalid chair constructed according to an embodiment of this invention.

Figure 2 is a detail side elevation of the chair.

Figure 3 is a fragmentary sectional view taken on the line 3—3 of Figure 1.

Figure 4 is a fragmentary sectional view taken on the line 4—4 of Figure 1.

Figure 5 is a sectional view taken on the line 5—5 of Figure 1.

Figure 6 is a fragmentary side elevation, partly in section, of the seat portion of the chair.

Figure 7 is a detail rear elevation of the chair.

Referring to the drawings, the numeral 10 designates generally a frame which is formed of a pair of longitudinally bowed back bars 11 which have secured to the lower end portions thereof lower horizontal side bars 12. Casters 13 are mounted in the lower ends of the back bars 11. The back bars 11 also have secured thereto at a point upwardly from the lower ends thereof, a pair of upper bars 14 which are parallel with the lower bars 12, and the bars 12 and 14 are fixed at the forward ends to front bars or tubes 15.

The lower ends of the tubes or bars 15 have secured thereto front casters 16. The front bars or tubes 15 are connected together by upper and lower tubes or bars 17 and 18 respectively. The back members 11 have secured therebetween a

back rest 19, which is secured to pairs of lugs 20 carried by the inner rear portions of the back members 11, and fastening means 21 extend through the lugs for securing the back member 19 in operative position. As shown in Figure 3, the back members 11 are of tubular construction and the upper ends thereof are closed by means of plugs 22, secured by fastening pins 23 or the like.

The frame 10 has secured therein a seat member 24. The seat member 24 is formed at the forward lower portion thereof with sockets 25 within which the upper ends of the front members 15 are adapted to engage, and countersunk bolts 26 extend downwardly through the seat member 24 and also extend through the upper side members 14. Spacer blocks 27 are interposed between the lower side of the seat member 24 and the upper bars 14, as shown in Figure 6. The seat member 24 is formed with an elliptical opening 28 which is elongated from the front to the rear of the seat member.

The seat member 24 is preferably of such a height that it will freely engage over the top of a toilet bowl B, as shown in Figure 7, and is also of a height such as to permit an invalid or patient to move in a horizontal direction from a bed 28, onto the seat 24, without undue exertion.

In order to provide for the movement of the patient from the bed 28 to the seat 24, I have provided an extensible seat member 29 which is pivotally carried by one of the side members 14. The extensible seat member 29 has secured to the lower side thereof, hinge bars 30 which are adapted to hold the upper side of the seat extension 29 substantially coplanar with the seat 24 when the outer free end of the seat extension is resting on top of the bed 28. The outer edge of the seat extension 29 is beveled, as at 31, so that the patient can be freely slid laterally from the bed 28 onto the extension 29, and then onto the seat 24.

The chair also includes a foot rest 32. The foot rest 32 includes a plate 33 which is hingedly secured by means of hinged bars 34 to the lower front bar or tube 18. Pivotally connected links 35 are secured, as at 36, to the plate 24, and are also pivotally secured, as at 37, to the upright front members 15. In this manner the foot rest 32 can be either collapsed to the position shown in Figure 3 with the plate 33 extending upwardly and between the front bars 15, or the foot rest can be extended so as to be positioned in a horizontal position as shown in Figure 2.

In the use and operation of this device, the patient who is in bed may be moved onto the chair

by moving the chair alongside the bed and then raising the seat extension 29 to the position shown in Figure 1. The patient may then be moved horizontally over the extension 29 onto the seat and may then be disposed in a seated position. The chair with the patient thereon may then be moved so that the frame of the chair will straddle the toilet bowl B.

I do not mean to confine myself to the exact details of construction herein disclosed, but claim all variations falling within the purview of the appended claim.

What I claim is:

A toilet chair comprising a frame formed of a pair of parallel upright back members, upper and lower side members fixed to said back members and extending forwardly therefrom, front legs fixed to said side members, upper and lower front members connecting said legs together, a seat, means securing said seat on said legs and said upper side members, a seat extension, means hingedly securing said seat extension to one of

5 said upper side members whereby said extension will normally be disposed in vertical dependent inoperative position and may be swung upwardly to horizontal operative position substantially coplanar with said seat, and a back rest secured between the upper portions of said back members.

HAROLD O. WOODS.
